TICKET PRINTING OR MARKING AND ISSUING MACHINE

Filed Aug. 31, 1928

50
Anthony W. Wood
by Cunderson. August 1868, etc.

UNITED STATES PATENT OFFICE.

ANTHONY WHITE WOOD, OF UPPER NORWOOD, LONDON, ENGLAND.

TICKET PRINTING OR MARKING AND ISSUING MACHINE.

Application filed August 31, 1928, Serial No. 303,347, and in Great Britain June 11, 1927.

This invention relates to portable ticket marking and issuing machines such as have been proposed for the use of tramway vehicles and omnibus conductors, railway attendants and others, and has reference to such machines of the kind comprising rotatable marking means within a casing, exterior means for setting the marking means and operating means for causing relative movement between the marking means and a platen or the like to effect the marking of the ticket as required.

The chief object of the present invention is to provide various improvements in this type of machine which enable a compact and easily operated machine to be produced.

According to one feature of the present invention the marking means which may print, emboss, perforate or otherwise mark the ticket are mounted so as to be rotatable about a horizontal axis (or more than one) which is parallel with the back of the machine and the ticket strip is caused to pass through the machine in a horizontal path parallel with the back of the machine when moving into the marking position and to emerge or issue from one side of the machine after having been marked. When the marking means comprise wheels, drums or the like having peripheral marking devices, they may be disposed on or around a horizontal shaft, barrel or the like parallel with the back of the machine so as to be rotatable together or independently. In the case of two or more wheels or drums which are used for the same purpose, say for marking fare stages of which there may be a considerable number, a "carrying over" mechanism is provided for the successive operation of the said wheels or drums. Another feature of the present invention is that the handle (which may be a rotatable wheel or drum) for setting the marking means is so constructed that the conductor's finger can be placed at any one of a series of positions thereon representing say different fare values, whereupon the said handle or member can be moved or rotated until the finger positioned as aforesaid comes into contact with a stop or the like thereby setting the marking means, say the fare marking means, to the required position ready for marking the ticket.

Another feature of the invention is that an ejector device is adapted to be laterally moved within the machine by operating an exterior handle or lever in such manner as to

engage with the ticket strip and cause the same to be pushed or projected through an opening in the side of the machine after the ticket has been marked so that the marked portion constituting the ticket and projecting through the side of the machine can be gripped so as to be severed from the ticket strip. When the marking of the ticket is effected by printing, a piece of carbon ribbon or strip in a frame or the like may, according to a further feature of this invention, be loosely and detachably interposed between the type on the marking drums or wheels and the platen so that the printing can be effected at different places on the carbon strip to avoid continual or repeated printing at one position thereon. A further feature of the invention is the provision of a movable top or cover which can be depressed for the purpose of effecting the marking of the ticket, and for this purpose the said movable top or cover may be depressed to cause the platen to move or press against the marking means. A machine having the characteristics above referred to may also comprise improved means for perforating a record strip in accordance with the value of the fare paid each time the ticket is marked to indicate the fare paid, so that this record strip having perforations corresponding to or representing the different fares paid in conjunction with other perforations representing other conditions or characteristics if desired can when removed from the machine be used in a statistical machine in connection with the compilation of statistics pertaining to passenger traffic or for traffic analysis. The said mechanism for perforating the record strip as aforesaid may be disposed entirely at one side or part of the machine and the means employed for selecting and setting the fare marking means may be employed for simultaneously setting perforating devices that perforate the record strip in such manner as to agree with the value of the fare paid which is to be marked on the ticket by the aforesaid marking means. The mechanism for causing the ticket strip to be marked, for example the aforesaid movable top or cover may also be utilized to operate the punches or the like that perforate the record strip.

In order that the said invention may be clearly understood and readily carried into effect, the same will now be described more

fully with reference to the accompanying diagrammatic drawings, in which:-

Figure 1 is a front view of the interior mechanism of one construction of the machine.

Figure 2 is a transverse sectional view taken on the line 2—2 of Figure 1.

Figure 3 is a plan view of the mechanism shown in Figure 1 with the cover plate removed.

Figure 4 is a transverse sectional view taken on the line 4—4 of Figure 1.

Figures 5, 6, 7 and 8 are detail views hereinafter referred to.

The mechanism is mounted on a plate 1 to form a unit that can be inserted in a box or casing 2 (shown in dotted lines in Figure 1) through the upper open end thereof, the said box having a carrying strap fitted thereto and being covered at its upper part by a sliding cover plate 3 that has a skirt 4 fitting around the said box or casing 2. In this example the fare marking wheel 5 is rigidly mounted on a barrel or shaft 6 rotatably mounted in suitable bearings 7 carried on the back plate 1, the outer end of the said barrel or shaft having a setting wheel or disc 8 for rotating the said barrel or shaft 6 and setting the fare marking wheel 5 against the action of a suitable spring (not shown). The said setting wheel or disc 8 is provided with depressions 9 as shown in Figure 5 which are marked to indicate different fare values. The said fare marking wheel 5 is set by the conductor placing a finger in any of the depressions 9 around the said setting wheel 8 corresponding to the value of the fare paid and rotating the said wheel 8 until the finger comes into contact with a fixed stop 10 see Figure 5 mounted on the casing so as to cause the barrel or shaft 6 with the fare marking wheel 5 thereon to be rotated to bring the marking means on the said marking wheel 5 corresponding to the value of the fare paid into the position for effecting the marking of the ticket. This movement is effected against the action of a spring not shown which may be contained within the fare marking wheel 5 and is attached at one end to the barrel or shaft 6 and at the other end to an adjacent fixed part. The fare marking wheel 5 is retained in the set position by means of a pawl 11 engaging with a ratchet wheel 12 on the side of the fare marking wheel. The other fare marking wheels or devices are mounted on a barrel or shaft 13 in alignment with the aforesaid barrel or shaft 6 but separate therefrom so that it can be rotated independently. Loosely mounted on this separate barrel or shaft is a wheel or segment 14 bearing indications such as "Mid-day tickets", "Through tickets", "Children's tickets" etc., and this may for example be set in the required position by a lever 15 that can engage a ratchet

wheel 16 on this marking segment which is moved against the action of a spring, not shown, and retained in the desired position by means of a pawl 17 engaging with the ratchet wheel secured to this segment 14. Fixed on the said barrel or shaft 13 is the "units" fare stage wheel 18 which by means of any suitable or known constructions of carrying over mechanism 19 operates the "tens" wheel 20. For the purpose of setting the wheel 18 a lever projecting into the interior of the casing may be provided or as shown a knurled wheel 21 may be provided on the outer end of the shaft 13 so that the latter can be rotated in order to set the fare stage wheel 18 to the desired position in which it is retained by means of a spring controlled arm 22 mounted on a rocking shaft 23 and bearing against the teeth of the toothed wheel 24 which is fixed to rotate with the said units fare stage wheel 18. The ticket strip 25 which is shown in the form of a folded pack but may be a roll, may be inserted into a space 26 through a closable opening in the casing 2 and the strip passes over a platen 27 whence it emerges through an opening in the side of the casing. The platen 27 is adapted to be raised for the purpose of pressing the ticket strip against the type on the said marking wheels or segments for printing the ticket through a carbon strip 28 which is contained in a metal frame 29 and adapted to be readily inserted between the platen and the said marking wheels and to be loosely held in position. For effecting the printing or marking operation the cover plate 3 is adapted to be slidably moved or depressed sharply by the conductor. The said cover plate has a series of rods 30 which pass through holes in the bearings or blocks 7 attached to the back plate of the machine, springs 31 being interposed between the said cover plate and the bearings or blocks 7 around the rods as shown in Figures 1 and 2. One of these rods is adapted to bear on a bar 32 carried on the outer end of a rocking member 33 in such manner that when the rocking member is depressed by the said rod 30 on the cover plate 3 engaging the bar 32 the other or inner end of the latter bearing on the middle part of the platen 27 raises the latter, the said platen being carried on movable links 34 pivotally mounted on fixed pins 35 secured to the back plate of the machine so that when it is raised in the manner aforesaid it presses the ticket strip and the carbon strip against the type on the various marking wheels to print the ticket with the desired particulars. The platen is normally retained in the lower position by means of a spring which may be secured to a casing (not shown) that fits over the rocking member 33 and the links 34 and which maintains the rocking member 33 in a horizontal position with its end bar 30

ready to be actuated by the aforesaid rod 30 on the depressible cover plate 3. After the cover plate has been depressed to effect the printing operation in the manner described it is returned to the normal position by means of the springs 31. The upper part of the casing containing the platen and the links 34 and rocking member 33 may be formed with guides or runners on which the outer parts or edges of the ticket strip can be supported. In order to cause the ticket after having been printed to be issued from the machine a slidable device or frame 36 is provided and this is normally retained in a raised position with spring fingers 37 at its ends out of engagement with the ticket strip. Inclined faces 38 are provided on the said frame 36 so that by causing the latter to be moved in the bearings 7 against the action of a spring 39, the inclined faces press against the bearing 7 to cause the frame 36 to be lowered so that the fingers 37 project on to the outer parts or edges of the ticket strip resting on the aforesaid guides or runners, and cause the strip to be moved forward along the guides or runners so as to project through the opening in the side of the casing. A series of transverse perforations are provided in the ticket strip to divide the ticket into a number of sections representing a number of tickets and when the strip is moved forward in the manner aforesaid, the perforations are adapted to engage with fixed pins 40 or the like so that the projecting part of the ticket can be readily torn off or severed at the said perforations. For the purpose of moving the frame 36 a two-arm lever 41 is pivotally mounted on the back plate of the frame, and adapted to receive a handle or trigger 42 which can be inserted through a slot in the casing 2 so as to fix on to the lever 41 which can be depressed against the action of a spring. The operating handle or trigger 42 is so placed that it can be operated by the lower part of the hand when in position for severing or tearing off the printed or projecting ticket. The upper end of the said lever 41 which is adapted to engage with a pin or the like on the said frame 36 in order to cause it to move for ejecting the ticket is also adapted to engage with an arm 43 mounted on the pin or spindle 44 carrying the aforesaid pawls 11 and 17. The arm 43 is provided with a bevelled or inclined surface so that when it is engaged by the said lever 41 it is moved so as to rock the pin 44 and raise the said pawls 11 and 17 out of engagement with the aforesaid ratchet wheels 12 and 16 thereby enabling the fare printing wheel 5 and also the printing segment 14 to be returned to the normal or zero position by springs not shown. If desired means may be provided whereby the setting of the fare marking wheel effects the setting

of marking devices or wheels that mark fare stages such as destinations on the ticket and for this purpose the latter wheels or the shaft carrying them may be connected or geared to the fare marking wheel or the like. 70

The perforating mechanism for perforating the record strip in this example is adapted to be actuated by gearing from the aforesaid barrel or shaft 6 carrying the fare marking wheel 5. The record strip 45 is adapted to be unwound from a spool 46 on to a spool 47 and it passes through a die 48 having holes to receive punches or perforators 49 which are retained in a raised position in the said holes by means of springs 50 and which are adapted to be depressed against the action of the said springs for perforating the record strip. In the example shown a series of perforators are 80 adapted to be used singly or in different groups or combinations in order to provide holes in different positions or different groups or combinations of holes to represent the different fare values indicated on the aforesaid fare marking wheel 5. For the purpose of depressing the perforators according to the value of the fare, a rotatable selecting cylinder 51 is mounted in the aforesaid depressible cover plate 3 in a position above the punches or perforators 49 and it is provided with a series of holes 52 in conjunction with plain or blank surfaces 53 (see Figure 8), which latter are adapted to be pressed against the upper ends of the punches or perforators 49 to depress those of the latter which are so engaged whilst the holes 52 permit the aforesaid selecting cylinder 51 to be depressed to move without depressing those perforators which are fitting in the said holes so that only the selected perforator or perforators are operated. The holes 52 are placed at different positions along and around the selecting cylinder 51 and the arrangement may be such that different perforators or combinations of perforators can be operated according to the angular position of the selecting cylinder to perforate the record strip accordingly. The said selecting cylinder 51 is adapted to be angularly moved or rotated by means of a crown wheel 54 or the like on the shaft 6 carrying the fare marking wheel 5 engaging with a pinion 55 on a vertical spindle or arbor 56, the upper end of which has an elongated pinion 57 which is engaged by a crown wheel 58 on the aforesaid selecting cylinder 51. The elongated pinion 57 permits of the crown wheel 58 on the said cylinder 51 being moved downwardly when the cover plate 3 carrying the said cylinder is depressed in order that the plain or blank surfaces and the holes therein can be brought into the operative position for actuating the punches or perforators 49. Therefore when 85 90 95 100 105 110 115 120 125 30

the fare marking wheel is set by the setting handle 8 as hereinbefore described, the selecting cylinder 51 is rotated to bring the corresponding series of holes and blanks into the position for enabling the corresponding perforator or perforators to be depressed for perforating the ticket with a hole or series of holes corresponding to the value of the fare paid. In this example a clockwork spring device 58 may be provided for causing the record strip 45 to be unwound from the spool 46 on to the spool 47. The record strip is provided with a series of positioning holes 59 throughout its length which are engaged by teeth or pins on a toothed wheel 60 rotatably mounted in the said die 48. This wheel 60 is normally held against rotation by a pivoted spring controlled pallet or release device 61 which is adapted to be operated under certain conditions to free the controlling wheel 60 in order to allow the record strip to be moved forward to the extent of one step after having been perforated. For this purpose a depending projection 62 on the cover plate 3 may engage with the tail of the pallet 61 in order to rock the latter so that it allows the tension on the record strip due to the clockwork spring to rotate the controlling wheel and also the spool 46 to the extent of one tooth. In addition to this perforating mechanism, a perforating device is provided for marking the record strip with a hole each time a fare stage is reached. For this purpose the units fare stage wheel 18 in being moved to indicate the fare stage, causes the arm 22 on the rockable spindle 23 to be moved by a tooth on the toothed wheel 24 engaging with the said arm so that the spindle 23 is rocked and depresses an arm 63 fixed thereon, which is adapted to bear at its free end on an additional punch or perforator 64 mounted in the said die 48 so that this punch can be moved downwardly against a spring when the arm 63 is so rocked to perforate the record strip with a hole which represents the fare stage. After a fare stage hole has been punched in the record strip it is necessary to operate the aforesaid pallet 61 to enable the record strip to be moved a step forward and for this purpose another arm 65 may be fixed on the said spindle 23 to engage with the tail of the pallet in order to rock the same so that the said controlling wheel 60 is released to allow the record strip to be moved by the clockwork spring 58.

Step by step counting devices may be provided and one of these devices 66 may be located in a position so as to be operated by a gear wheel on the shaft 6 carrying the fare marking wheel 5 so that it shows the total amount of the different fares paid. Another counting device 67 may be provided and this is adapted to be operated by one of the rods 30 on the cover plate 3 each time

the latter is depressed so that this counting mechanism indicates the number of times the lid is depressed and therefore the number of tickets issued. In order that the positions of the fare stage wheels may be readily observed, a series of numbers representing units may be marked on the face of the operating wheel 21 (see Figure 7) that sets the fare stage wheel, and numbers representing "tens" may be provided on a disc 68 fixed on a rotatable pin or spindle carrying one of the toothed wheels of the carry over mechanism 19. Arrows or the like may be provided on the casing as shown so that the positions of the numbered disc 68 and wheel 21 can be readily observed to indicate the positions of the fare stage wheels.

What I claim and desire to secure by Letters Patent of the United States is:—

1. In a ticket marking and issuing machine, the combination of a casing, a plurality of marking members adjustable about a common axis within the casing, means extending to the exterior of the casing for adjusting said members about said axis, a platen, a strip of paper supported within the casing and extending between the platen and marking members to an opening in a wall of the casing, said strip being provided with a plurality of longitudinally spaced transverse rows of perforations, means for effecting relative movement between the platen and marking members to print on the section of the paper strip positioned between them, means for feeding the strip longitudinally through the said opening in the casing, and a plurality of pins supported by the casing and adapted to enter the row of perforations in the strip adjacent the said opening.

2. A machine as in claim 1 comprising an ejector for causing a marked ticket to issue from a side of the machine and means whereby the marking means will be returned to initial position when the ejector device is operated.

3. A machine as in claim 1 including a record strip, means for moving the record strip in the machine, punches for perforating the record strip when the fare marking device marks the ticket strip, and means whereby additional punching means can be operated by the fare stage marking device so as to punch holes in the record strip to indicate the fare stages.

4. A machine as in claim 1 comprising means for receiving a record strip in the machine, punches for perforating said record strip, means for operating the punches when the ticket marking means are actuated, a die through which the record strip is moved and which co-operates with the said punches, a toothed wheel engaging holes in the said record strip, and an escapement device for controlling movement of said wheel.

5. A machine as in claim 1 comprising means for moving a record strip, punches for perforating said strip, a selecting device for enabling the required punches to be selected, and a movable top adapted to be operated to actuate the ticket marking means and also to move said selecting device and cause the selected punches to perforate the record strip.
- 10 6. A machine as in claim 1 comprising a casing having a movable top slidably mounted on the machine so that it can be depressed, and means whereby the depression of the said top causes the platen to be raised in relation to the marking members.
- 15 7. A portable ticket marking and issuing machine of the kind referred to, comprising a fare marking device, a platen for cooperating with said marking device, a ticket strip, a record strip, a record strip, means for moving the record strip, punches for perforating the record strip, a die containing said punches, selector means synchronized with the fare marking device so as to be set by the latter to operate the required punches when the fare
- 20
- 25
- marking device marks the ticket strip, an additional punch in the said die, and independent means for automatically operating the additional punch to perforate the record strip to indicate fare stages thereon upon 30 operation of the machine.
8. A portable ticket marking and issuing machine of the kind referred to, comprising a fare marking device, a fare stage marking device, a platen for cooperating with said marking devices, a ticket strip, a record strip, means for moving the record strip, a die containing said punches, selector means synchronized with the fare marking device 35 40 so as to be set by the latter to operate the required punches when the fare marking device marks the ticket strip, an additional punch in said die and means whereby the operation of the fare stage marking device 45 automatically sets the additional punch to perforate the record strip to indicate fare stages upon operation of the machine.

ANTHONY WHITE WOOD.
